[57]**CLAIM**

The ornamental design for foil pan packaging, as shown and described.

DESCRIPTION

FIG. 1 is a top plan view of the foil pan packaging of the invention;

FIG. 2 is a side elevational view of the foil pan packaging of FIG. 1;

FIG. 3 is a top plan view of a second embodiment of the foil pan packaging of the invention;

FIG. 4 is a side elevational view of the foil pan packaging of FIG. 3;

FIG. 5 is a top plan view of a third embodiment of the foil pan packaging of the invention; and,

FIG. 6 is a side elevational view of the foil pan packaging of FIG. 5.

The bottom is plain and unornamented. The sides not shown are disclaimed.
